W. B. ARNOLD.
WELT FOR BOOTS AND SHOES.
APPLICATION FILED DEC. 26, 1916. RENEWED NOV. 15, 1917.
1,307,174.

Patented June 17, 1919.

UNITED STATES PATENT OFFICE.

WILLIAM B. ARNOLD, OF NORTH ABINGTON, MASSACHUSETTS.

WELT FOR BOOTS AND SHOES.

1,307,174.

Specification of Letters Patent. Patented June 17, 1919.

Application filed December 26, 1916, Serial No. 138,719. Renewed November 15, 1917. Serial No. 202,243.

To all whom it may concern:

Be it known that I, WILLIAM B. ARNOLD, a citizen of the United States, residing at North Abington, in the county of Plymouth 5 and State of Massachusetts, have invented an Improvement in Welts for Boots and Shoes, of which the following description, in connection with the accompanying drawings, is a specification, like characters on the 10 drawings representing like parts.

The invention to be hereinafter described relates to welts for boots and shoes.

The welt is essentially in the form of a narrow strip and the inseam stitching must 15 be closely adjacent the inner edge of the welt, but yet a sufficient distance from said edge to leave enough stock to prevent the stitching from pulling or tearing through the marginal leather. Consequently the 20 leather used in making welts must be strong, tough, high grade material able reliably to bear heavy duty of holding the upper to the sole.

The high cost of the grade of leather used 25 for welts renders it important to employ as small an amount of leather therein as practicable without sacrifice of necessary strength. Obviously, a slight saving in material in the welts for a pair of shoes multiplies into 30 a big economy.

One of the objects of the present invention is to provide a welt requiring less material and having greater strength than welts heretofore used. Another object is to 35 increase the amount of welt material between the inseam stitching and the inner edge of the welt, without increasing the material required in the welt. Another object is to greatly reduce, if not entirely eliminate the 40 waste of welt material in trimming the edges of the inner sole flange, the upper and its lining. And still another object of the invention is to so cut the welt from stock that the outer edge will have a chamfer prior to 45 the rounding operation which will substantially reduce loss of welt stock in said operation.

The character of the invention may be best understood by reference to the following 50 description of an embodiment illustrating the same shown in the accompanying drawing, wherein.

Figure 1 is a transverse vertical section through a portion of an upper, its lining, 55 inner sole and welt illustrating the inven-

tion, showing the parts as they appear prior to trimming of the upper and its lining;

Fig. 2 is a view similar to Fig. 1 showing the parts as they appear after the trimming and beating out operation; 60

Fig. 3 is a perspective view of a portion of a welt strip as it appears prior to formation of the stitch receiving groove therein;

Fig. 4 is a view similar to Fig. 3 of the 65 welt strip as it appears after said groove has been formed therein;

Fig. 5 is a perspective view of the completed welt;

Fig. 6 is a transverse section through the 70 welt shown in Fig. 5;

Fig. 7 is a similar transverse section of a modification of the welt; and

Fig. 8 is a vertical transverse section 75 through a completed shoe equipped with a welt embodying the invention.

Referring to the drawings the welt shown therein as illustrating the invention may be formed by slitting a strip 1 (Fig. 3) from stock obliquely to the face of the stock thereby producing inner and outer bevel edges 80 3 and 5. Then the inner seam stitch receiving groove may be formed therein. In the present instance of the invention to accomplish this a slit 7 (Fig. 4) of substantial depth may be cut in the strip closely adjacent and if desired parallel to the inner bevel edge 3, thereby forming a lip 9. This 85 lip may then be bent outward and backward (Figs. 5 and 6) so that its outer face 11 is turned over upon the bevel edge 3 of the 90 strip.

Thus the width of welt stock between the groove and the inner edge of the welt is substantially doubled and a strong shoulder 95 15 is provided which will effectively resist tearing of the stitching through the stock. It will be noted the groove is formed without removal of stock from the strip, and that the material which is spread outward to open the groove, instead of being lost, is 100 utilized to contribute to the strength of the welt.

Having described the construction of the welt, its application to a shoe will now be described with more particular reference to 105 Figs. 1 and 2, wherein is shown an inner sole 17 having a stitch receiving and retaining flange or shoulder 19 terminating in a lip 21 which forms a continuation of the feather edge 22 of said sole. The edge por- 110

tions of the upper 23 and its lining 24 are laid in the recess formed by said lip and feather edge, and are bent inward to conform to said recess.

5 The welt is then presented to the upper with the margin 25 of its grain face against said upper, and the inner sole, upper, its lining and the welt are stitched securely together with the stitches 27 embracing the 10 inner sole flange 19 and welt shoulder 15.

The slit in the welt receiving the stitching permits the welt stock between the stitching and the upper to readily bend laterally to allow the body of the welt to lie substantially in the same plane as the inner sole as will be noted in Fig. 1, but said stock will not project out materially from the face of the body of the welt. Consequently the edges of 15 the upper, its lining and the inner sole flange 20 may be readily trimmed (Fig. 2) substantially without removal of stock from the welt.

• After beating out the welt in the usual way a filler 29 (Fig. 8) is laid on the inner 25 sole within the boundary of the welt, and the latter is stitched to the outer sole 31 as will be noted in Fig. 8.

The narrow margin of the outer bevel or 30 chamfer edge 5 projecting slightly beyond the outer sole is then trimmed off and the edges of the welt 1 and outer sole are rounded. Heretofore it has been necessary to skive off a portion of the outer edge of the welt in the finishing operation; but since 35 the welt strip is beveled in severing the same from stock, there is no loss of welt stock in producing this bevel, and again a further saving in the welt stock is obtained.

In some cases in making the welt the 40 lip 9 turned over against the outer bevel edge 5 may be cemented thereto as at 33 (Fig. 7) if desired, although this is not indispensable as the presence of the stitching in the groove and the engagement of the 45 outer sole with said lip tend to maintain the latter in its proper turned over position.

The welt may be easily manufactured in long strips which may be cut into appropriate lengths for the shoes as required.

50 The angle of the inner edge with respect to the faces of the welt may obviously be varied according to conditions as desired.

By the invention described it will be apparent that the effective width of the welt is 55 increased without increase in the width of

material required for making the welt. As a result less material is required to produce a welt of the necessary strength than heretofore employed, and a valuable saving in the high grade expensive leather used for welts 60 is obtained.

It will be understood that the invention is not limited to the specific forms shown, but extensive deviations may be made therefrom without departing from the spirit and 65 scope of the invention as defined in the appended claims.

What is claimed is:

1. A welt comprising a body having an inner bevel edge and a lip slotted from said 70 body adjacent said edge turned over toward said edge and forming an inner seam groove and a stitch resisting shoulder.

2. A welt comprising a body having inner 75 and outer bevel edges and a lip adjacent said inner edge turned over toward the latter and forming an inner seam groove and a stitch resisting shoulder.

3. A welt comprising a body having a lip adjacent the inner edge thereof turned over 80 toward said edge and forming a stitch receiving groove and a stitch resisting shoulder.

4. A welt comprising a body having a marginal portion doubled over and forming 85 an inner seam groove and a substantial stitch resisting shoulder between said groove and the inner edge of said body.

5. A welt comprising a body having a marginal portion turned over toward an 90 edge thereof and forming an inner seam groove and a stitch resisting shoulder substantially as thick as the body of the welt.

6. A welt comprising a body having a bevel edge with a longitudinal marginal 95 portion turned over toward said edge for increasing the effective width of the welt.

7. A welt comprising a body having a longitudinal lip adjacent an edge thereof turned over and secured to said edge and 100 forming a stitch receiving groove.

8. A welt comprising a body having a longitudinal groove adjacent an edge thereof and a portion between said groove and edge turned over toward a face of said body to 105 present a substantial shoulder between said groove and edge.

In testimony whereof, I have signed my name to this specification.

WILLIAM B. ARNOLD.
